Jos. D. McMullen
ATTORNEY

UNITED STATES PATENT OFFICE.

CHARLES R. KRAUTHOFF, OF WASHINGTON, DISTRICT OF COLUMBIA.

MASSAGING DEVICE.

Application filed May 23, 1925. Serial No. 32,497.

To all whom it may concern:

Be it known that I, CHARLES R. KRAUTHOFF, a citizen of the United States, and a resident of Washington, District of Columbia, have invented a new and useful Improvement in a Massaging Device, of which the following description, in conjunction with the accompanying drawings, is a specification.

10 This invention relates to a massaging device and consists in certain peculiarities of construction, novel arrangement and operation of the various parts thereof, as will be hereinafter more fully set forth and specifically claimed.

15 The principal object of the invention is to provide a massaging device which shall be of simple, durable and inexpensive construction, easily manipulated, efficient in 20 operation and which adjusts itself to most effectively massage any part of the body.

25 A further object is to provide a massaging device which thoroughly kneads or manipulates the flesh by a combined opposite lateral movement and cupping thereof, thus giving the flesh a succession of undulations in opposite directions and at the same time depressing and raising the flesh at certain 30 intervals all of which will be brought out further in the following description.

Briefly stated this invention comprises a massaging device consisting of a frame or holder on which is pivotally mounted a plurality of helically grooved friction rollers, having a spirally arranged series of 35 suction openings, the rollers being mounted to assume various positions depending on the contour of the surface over which they are passed.

40 Referring more particularly to the accompanying drawings in which corresponding parts are indicated by similar reference characters:

45 Fig. 1 is a top plan view showing the rollers with their longitudinal axes lying within the same plane.

Fig. 2 is a side elevation showing the rollers with their longitudinal axes lying in different planes, and

Fig. 3 is a perspective of the frame with 50 the rollers removed.

In the familiar types of massaging devices now in use the limited movement of the flesh under the action of the rollers and lack of adjustability reduces the efficiency of said devices.

It is therefore the aim and purpose of this invention to effect a massaging device which owing to its simplicity and adjustability provides a most efficient and inexpensive means for thoroughly massaging any portion of the body.

In the illustrated embodiment characterizing this invention (1) indicates a yoke shaped supporting frame fastened centrally to a handle (2) either end of said yoke being bent at (3) to form clamping forks (4), the extremities of said forks being bent inwardly and rounded or knobbed to form trunnions (5). Fastened permanently to 60 the supporting frame (1) at the bent portion (3), and positioned normally to the frame are segmental sleeves (6), in which are slidably mounted semicircular guides 65 (7). These semicircular guides (7) are also 70 bent normally at their extremities and rounded or knobbed to form trunnions (8) and (9). The trunnions (5) which are located at the extremities of the clamping forks (4) have adjacently mounted flanges 75 (10). On these trunnions are pivotally 80 mounted cross-arms (11).

These cross-arms contain circular openings located centrally at (12) and at either end at (13) and (14). The trunnions (5) 85 of the clamping forks (4) project through the openings (12) and thus form a pivotal connection for the cross-arms (11), whereas in the case of the trunnions (8) and (9) which project through the openings (13) 90 and (14), they are held rigidly in place in the cross-arm, since the cross-arms (11) are rigidly fastened to the semicircular guides (7) at either end.

The friction rollers (16), (17) and (18) 95 are grooved spirally as shown in Fig. 1, the grooves and corresponding mounds being indicated by (19) and (20) respectively.

At suitable intervals along the crest of the mounds throughout the entire axial length of the rollers are suitably shaped depressions or vacuum cups (21). These depressions are of sufficient depth to cause a sucking or cupping of the flesh as the roller is passed over the same.

At the ends of the rollers (16), (17) and (18) are located journals which are composed of a flange (22) and a bearing portion (23) mounted in cylindrically drilled holes (24). In these journals are mounted the trunnions (5) of the clamping forks (4) and trunnions (8) and (9) of the semi-circular guides (7).

Since the diameter of the holes (24) into which the journals are fitted are larger than the diameter of the knobbed trunnions the clearance thus provided permits a swiveling action of the rollers, thus permitting the rollers to assume a variety of positions in relation to one another and to thereby conform to the contour of the body as they are passed over the same.

In the operation of this device as the rollers are passed over the body they move the flesh from side to side in opposite undulations or waves which are produced by the alternate oppositely spiraled surfaces of the rollers, and as cups 21 are brought into and out of firm contact with the flesh as the device is moved along they raise the same and release it thus producing a cupping effect.

In conclusion it is evident this invention provides a massaging device which if regularly applied will stimulate the action of the skin, increase circulation of the blood and afford general body development dependent on the requirements of the patient.

Although in the foregoing certain components have been defined as best adapted to perform the functions allotted to them, nevertheless it is to be understood that various minor changes may be resorted to within the scope of the appended claims without departing from or sacrificing any of the principles of this invention.

Having described my invention, what I claim as new and wish to secure by Letters Patent is:

1. A massaging device comprising a plurality of normally parallel rollers having spirally formed surfaces, the spirals of the respective rollers being inversely arranged, a mounting journalling the extremities of the rollers and means in connection with such mounting to permit relative angular movement of the rollers so that they will conform to the contour of the surface over which they are caused to travel.

2. A massaging device comprising a plurality of normally parallel rollers having their surfaces spirally formed and provided with a series of cupping openings the spirals of the respective rollers being inversely ar-

ranged, a mounting journalling the extremities of the rollers and means in connection with such mounting to permit relative angular roller adjustment to the contour of the surface over which they are caused to travel. 70

3. A massaging device comprising a plurality of normally parallel rollers having spirally formed surfaces, the spirals of the respective rollers proceeding in opposite directions and the surfaces of the rollers being formed with a spiralling series of cupping openings, a mounting for the rollers journalling their extremities and means in connection with such mounting to permit relative angular movement of the rollers so that they will conform to the contour of the surface over which they are caused to travel. 75

4. A massaging device comprising a trio of normally parallel rollers having spirally formed surfaces and provided with a plurality of cupping openings, the spiral of the innermost roller being inverse to that of the outermost rollers, a mounting journalling the extremities of the rollers and means in connection with such mounting to permit angular movement of the outermost rollers with respect to the innermost roller to maintain the rollers in contact with the surface over which they are caused to travel, regardless of the contour of said surface. 80

5. A massaging device comprising a frame, a roller supporting cross-arm swivelly mounted at each end of the frame, a trio of normally parallel rollers arranged between the cross-arms, the outermost rollers being rotatably connected to the extremities and the intermediate roller to the pivotal point of the cross-arms to permit angular movement of the outermost rollers with respect to the intermediate roller to maintain said rollers in contact with the surface over which they are caused to pass regardless of the contour of said surface. 95

6. A massaging device comprising a frame, cross-arms swivelly mounted at each end of the frame, a trio of normally parallel rollers situated between the cross-arms, the outermost rollers of the trio being rotatably connected to the extremities of the cross-arms, the intermediate roller being connected to the pivotal point of said cross-arms to permit relative angular movement of the outermost rollers with respect to the innermost roller, said rollers having a series of cupping openings and being spirally formed, 110 the spiral of the intermediate roller being inverse to that of the outermost rollers. 120

7. A massaging device comprising a mounting, a plurality of oppositely spiralled rollers rotatably supported in said mounting, and means in connection with the said mounting to permit angular movement of said rollers in such a manner that they will conform to the contour of the surfaces over which they are passed. 125

8. A massaging device comprising a frame, including oppositely disposed end pieces, roller mountings carried in said end pieces and movable through an arc vertical with respect to the longitudinal axes of the frame, a plurality of rollers swivelly connected at their extremities to the mount- ing, the rollers being normally disposed in parallel relation, but susceptible of relative angular movement dependent upon the contour of the surface over which they are caused to travel. 10

CHARLES R. KRAUTHOFF.
